KNIFE BOX

Robert Hain, Edison, and Richard A. Warn, Sr., Milltown, N.J., assignors to Washington Forge, Inc., a corporation of New Jersey

Filed Feb. 6, 1968, Ser. No. 10,458

Term of patent 14 years

U.S. Cl. D44—29
Int. Cl. D3—99

We claim:

The ornamental design for a knife box, as shown.
